UNITED STATES PATENT OFFICE

PETER DE SIMONE, OF BROOKLYN, NEW YORK

HAT BLOCKING MACHINE

Application filed August 9, 1929. Serial No. 384,535.

My invention relates to hat blocking machines and more particularly aims to provide a novel and improved machine for centering the hat, clamping and stretching the brim, and shaping and blocking the crown.

The principal objects of my improvements are, first, to provide means for facilitating rapid centering of the hat; second, to provide efficient clamping means for the hat covering a large portion of its brim, while preventing localized strains therein; third, to provide easily operable means for shaping and blocking the crown; fourth, to provide simple means for stretching the brim evenly over its entire surface; and fifth, to incorporate all the foregoing in such combination that the machine as a whole shall be cheap to manufacture and easy and rapid to operate.

With these and other objects in view, the invention resides in certain novel construction and combinations and arrangements of parts, the essential features of which are hereinafter fully described and are particularly pointed out in the appended claims.

The preferred attainment of these various objects embodies a machine including among other things, a top plate supporting a centrally located well, which well contains a steam chest circumferentially enclosing a vertically operating member carrying the hat-block. The top plate is also provided with a plurality of radial slots acting as guides for sets of slidable clamps, said clamps adapted for gripping the hat brim and also adapted for outward sliding movements away from the central hat-block, for stretching the brim. There are also included actuators, as hand levers, and appropriate connecting linkage, for operating the brim gripping and stretching clamps, and a foot treadle, for operating the vertically moving hat-block.

In the accompanying drawings:

Figure 1 is a side elevation of such embodiment, partly in section;

Figure 2 is a top plan view, with the steam cover swung to the right;

Figure 3 is an enlarged vertical sectional view, taken on the line 3—3 of Figure 2 with

the steam cover swung to operative position over the hat block;

Figure 4 is an enlarged fragmentary horizontal sectional view, taken on the line 4—4 of Figure 3, showing particularly details of the brim clamp closing linkage;

Figure 5 is a similar view, taken on the line 5—5 of Figure 3, showing particularly details of the stretcher linkage for sliding the brim clamps toward or away from the center of the machine;

Figure 6 is a fragmentary perspective view of certain parts shown in Figures 3, 4 and 5 for making clearer the connections of both the brim clamp linkage and the stretcher linkage; and

Figure 7 is a detail sectional view, greatly enlarged, taken on the line 7—7 of Figure 5.

Similar reference characters refer to similar parts throughout the several views.

Referring now to the drawings in detail:

A top plate 1, having a central well 3 is secured to supporting corner legs 2.

Located within the well 3 is a steam chest 4, having a steam inlet pipe 5 and steam vents 6. This pipe 5 as shown in Figure 3, desirably has interposed therein a valve 5a; the pipe 5 (compare Fig. 1) leading to the interior of steam chest 4 by suitable connections including an elbow 5c. To the stem of the valve 5a is connected an actuator 5b which may for convenience be prolonged far enough to the right in Figure 3 to project beyond the front of the machine and be accessible to the operator handling the actuators 11, 37 and 42 hereinafter described.

The inner wall of the steam chest is preferably oval shaped, similar to the band section of a hat, and acts as the top guide member for a vertically operating hat block support 7, upon which rests a removable hat-block A, located by the usual dowel pins as shown.

The hat-block A may be of the flat bottom type, in which case it would rest directly upon the support 7, or it may be of the concave bottom type, in which latter case, a filler piece, substantially as shown on the support at B, may be used.

Rigidly fixed to the hat-block support 7 is

a tubular lift rod 8 sleeving a bottom rod-guide 9, shown fixed to the floor upon which the machine rests. Also fixed to the floor is a treadle bearing 10 acting as a fulcrum for a treadle 11, which latter pivots at its rear end a connecting link 12, this link at its other end being connected to a collar 13 adjustable on the lift rod 8 by means of a set-screw 14.

10 Mounted above the steam chest 4 is a steam cover 15, connected to top plate 1 by means of a universal joint 16, thus permitting such chest to be lifted and then swung to either side. Connected to said cover by a nipple 15a, is a flexible tube 15b, to supply the interior 15 of the cover with heating steam from a suitable source.

15 Formed in the top plate are a plurality of slotted openings 17 (eight in the embodiment shown) each acting as a guide for a sliding 20 yoke 18 (see Fig. 6), which yokes carry, as best shown in Figure 3, upper and lower retaining plates 19 and 20, this construction thus permitting only inward and outward 25 sliding movements of the yokes. Each upper retaining plate 19 at its outer end carries a pair of upstanding ears between which is pivoted a top brim clamp 21. These clamps 21 have their jaw portions 22 preferably of 30 greater lateral width than the main body or shank portions to more completely cover the hat brim. Each bottom brim clamp 23, of corresponding width, is rigidly secured to its 35 sliding yoke 18, the opposed jaws being normally separated by the compression spring 24.

40 Fixed to the top of each alternate sliding yoke is a flexible metallic member 25 having downturned ears 26 at each end, while each intermediate alternate sliding yoke has secured thereto a flexible metallic member 27 the ends of which are adapted to slip under the ears 26; thus forming a continuous flexible expanding centering compartment for rapidly centering the hat.

45 Thumb screws 28 passing through holes in the top brim clamps 21 are flexibly connected at their lower ends as shown in Fig. 3 to inclined cam levers 29 whose outer ends are pivotally connected to yokes 18 at 30. Each 50 lower retaining plate 20, as shown best in Figure 6, is considerably extended on one side to provide room for the pivot 31 for its associated clamp closing wedge 32, the lower 55 surface of which wedge is angularly formed to fit inclined cam lever 29 and whose upper surface slides underneath lower retaining plate 20. The opposite end of each wedge 32 is pivotally connected to a link 33, best 60 shown in Figure 4; one of these links connecting each of the wedges to an upper oscillating ring 34, mounted by means of rollers 35 for anti-friction movement around the well 3. Also connected to the oscillating ring is 65 a lever 36 adapted for push and pull opera-

tion by means of a brim clamp operating handle 37.

Pivots connected to the lower arm of each sliding yoke 18 (see Figures 3, 5, 6 and 7) 70 is a curved link 38 which connects each yoke to a lower oscillating ring 39 mounted by means of rollers 40 for anti-friction movement around the well 3. Formed integrally with the upper and lower flanges of this ring 75 is a handle member 41, best shown in Figures 5 and 7, adapted for rotation about the central axis of the machine by means of a brim stretcher operating handle 42.

The operation of the machine is as follows:

80 The hat is placed in the previously properly adjusted centering compartment, with the hat brim inserted between opposed clamping jaws 22 and 23 as shown at X in Figure 3, and the brim clamp operating handle 37 pushed in. By means of ring 34, links 33 and 85 wedges 32 are caused to take the position shown by the full lines of Figure 4, and wedges 32 depress cam levers 29 thus causing jaws 22 to clamp the hat brim between it and the relatively stationary jaw 23. The brim stretcher operating handle 42 is then rotated to the right, as shown by the full lines of Figure 5, and by means of the ring 39 and links 38, the yokes 18 carrying the brim clamps are 90 forced outward a uniform distance thus subjecting the brim to a uniform stretch of any desired amount.

95 Foot treadle 11 is then depressed raising the hat-block into the crown of the hat the desired amount. The hat may be banded by 100 means of a banding shell which if desired may be supported from the steam cover 15 (or a string not shown, may be tied around the hat at the band section, as is usually done in reshaping a hat). At the proper time in 105 the sequence of operations, steam may be admitted and will be discharged evenly over the hat by means of the numerous vents in the steam chest.

110 When the various operations of stretching the brim, banding, blocking the crown, steaming, etc., are completed, the brim clamping jaws are released and the hat, together with the hat-block, are removed from 115 the machine. Another hat-block (if required), and another hat, are then placed in the machine, and the operation repeated.

120 Obviously, the hereinbefore described construction admits of considerable modifications without departing from the invention; therefore, I do not wish to be limited to the precise arrangements shown and described, which are by way of illustration of a preferred way of carrying out the invention, merely.

125 What is claimed as new is:

1. In a hat blocking machine, in combination, a hat-block, brim stretching means, and a sectional flexible expanding device for cen- 130

tering the hat carried by said brim stretching means.

5 2. In a hat blocking machine, in combination, a vertically operating hat-block, brim clamping jaws adapted for outward movement for stretching purposes, and interconnected flexible members carried by the clamping jaws and forming an expanding and contracting centering ring.

10 3. In a hat blocking machine, in combination, a hat-block, sectional expansible centering means for a hat, and a plurality of circumferentially spaced brim clamping elements adapted for stretching the brim of 15 the hat when firmly clamped thereto, said clamping elements being arranged to provide almost a full contact with the annulus of the hat brim, said centering means engaging the hat outwardly of the fields of gripping operations of the clamping elements.

4. In a hat blocking machine, in combination, expansible centering means, a vertically operating hat-block, brim clamps, and means for moving the brim clamps toward or away 25 from the hat-block, said centering means engaging the hat outwardly of the fields of gripping operations of the clamping elements.

5. The combination of a vertically movable support, a steam chest around the support, a steam inlet and steam vents in said chest, a plurality of relatively wide jawed clamps radially movable in paths spaced about said support, means for moving said support vertically, means for closing all of said clamps simultaneously to engage the hat between the inner and outer peripheries of the brim, and means for simultaneously moving all of the clamps radially with respect to the support, and sectional expansible means for centering the hat by engaging the outer periphery of the brim.

40 6. The combination of a top plate having a central opening and a plurality of radial slots therein, leg supports for the top plate, a central circular well rigidly secured to the top plate, an annular steam chest located in said central opening and supported by said well and having a steam inlet and a plurality 45 of steam vents, a vertically movable support within the annular steam chest, a pair of jaw clamps in each of said radial slots, means for moving said movable support vertically, means for simultaneously closing all of said 50 jaw clamps to engage the hat between the inner and outer peripheries of the brim, and means for simultaneously bodily moving said jaw clamps in said radial slots, and sectional 55 expansible means for centering the hat by engaging the outer periphery of the brim.

60 7. In a hat blocking machine, in combination, a vertically movable hat-block, a plurality of brim clamps carrying interconnected sectional expanding centering means, a steam supply means, a foot treadle and associated

linkage for operating the hat-block, a hand lever and associated linkage for closing the brim clamps, and a second hand lever and associated linkage for sliding the brim clamps toward or away from the hat-block.

70

8. A clamping mechanism comprising a plate having a plurality of slots converging toward a common center, a sliding member in each of said slots, each said sliding member carrying a pair of clamping jaws, one of which is movable with respect to the other, spring means for opening said jaws, a cam link operable substantially parallel to the movable jaw and operably connected thereto, an adjustable link included in the connection 75 last mentioned and a wedge link for forcing the cam link downward and thereby closing the clamping jaws.

80

9. The combination defined in claim 8, wherein means are included for simultaneously 85 operating all of the wedge links.

10. A clamping and stretching mechanism comprising a support having a plurality of slots converging toward a common center, a sliding member in each of said slots, each said 90 sliding member carrying a pair of relatively movable clamping jaws, spring means for opening said jaws, cam devices, an adjustable link connecting each movable jaw and each cam device, a wedge link for forcing each 95 cam device downward and thereby closing the associated clamping jaw, means for simultaneously operating all of the wedge links, and means for divergently sliding all of the 100 sliding members simultaneously for the stretching action.

11. In a hat blocking machine, a support having a central opening and a plurality of slots converging toward the center, a tubular housing below said opening, an annular steam 105 chest located in said opening and supported in said housing and having a steam inlet and a plurality of steam vents, a vertically movable support within the annular steam chest, a sliding member in each of said slots, each 110 sliding member carrying a pair of clamping jaws, one of which is movable with respect to the other, means for opening said jaws, a cam link substantially parallel to the movable jaw, an adjustable link between said 115 movable jaw and said cam link, a wedge link for actuating said cam link, said adjustable link and said movable jaw downward, means for operating the vertically movable support, means for simultaneously operating all of the 120 wedge links, and means for simultaneously operating all of the sliding members.

In testimony whereof I hereby affix my signature.

PETER DE SIMONE. 125
